FIG. 1

FIG. 3

FIG. 2

FIG. 4

FIG. 5

INVENTOR.
BENJAMIN H. PELTON
BY *A. B. Bowman*
ATTORNEY

UNITED STATES PATENT OFFICE.

BENJAMIN H. PELTON, OF CARLSBAD, CALIFORNIA, ASSIGNOR TO B. H. PELTON, JR., OF CASPER, WYOMING.

LOCK.

Application filed January 25, 1926. Serial No. 88,518.

My invention relates to locks, more particularly to cylinder locks, although my improvements may be readily applied to other locks as well.

5 The objects of my invention are: first, to provide a lock having tumblers which may be readily removed for the substituting of others, whereby the combinations of the lock may be readily changed; second, to 10 provide a lock of this class which is particularly desirable for hotels, apartment houses or other structures where a large number of doors is employed, so that the combinations and keys for the different 15 doors may be easily and periodically changed, if desired; third, to provide a lock assembly having a tumbler assembly adapted to be readily removed from the outside of the door or the like upon which 20 it is mounted for substituting another tumbler assembly without dismounting the lock assembly or removing any other main portion thereof; fourth, to provide a lock structure having a separate tumbler assembly, 25 which, when the lock is mounted in the door or associated member, may be readily removed from the lock structure for substituting another adapted to be operated by a different combination of key bit or an entirely 30 different key, if desired; fifth, to provide a lock structure of this class in which the cylinder or tumbler casing, when applied to a conventional cylinder lock, may be easily and quickly released from the inner 35 side of the door or other member upon which the lock is mounted and removed from the outside of the door or other member and another quickly and easily substituted; sixth, to provide as a whole a novelly 40 constructed lock, and seventh, to provide a lock structure of this class which is particularly simple and economical of construction, durable, efficient, which may be readily changed by any inexperienced person 45 and with a minimum of tools, and a lock structure of this class which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had 55 to the accompanying drawings and to the

characters of reference thereon, which form a part of this application, in which:

Figure 1 is a side elevational view of my lock structure, showing the same mounted in a door, shown fragmentarily, with the view 60 taken looking towards the edge of the door, and showing certain parts and portions of the lock structure broken away and in section to facilitate the illustration; Fig. 2 is a top view thereof, also showing certain 65 parts and portions of the lock structure broken away and in section to facilitate the illustration; Fig. 3 is a sectional view thereof, taken through 3—3 of Fig. 1; Fig. 4 is a sectional view thereof, taken through 4—4 70 of Fig. 2, and Fig. 5 is a partial sectional and partial elevational view thereof, taken on the line 5—5 of Fig. 2.

Like characters of refer to similar parts and portions throughout the several views 75 of the drawings.

The lock shown in the drawings is similar in construction to conventional locks now in use for doors. The lock shown in the drawings is a type of the commonly known "cylinder lock" and consists essentially of a bolt casing 1 secured at the inner side and near the free edge of the door D, a bolt 2 reciprocally mounted in the casing 1 and normally held in an outward position by a compression spring 3 positioned around the inner reduced shank end of the bolt 2 between a plate 1^a within the casing 1 and a shoulder near the outer end of the bolt 2, a bolt operating plate 4 secured to the inner 80 end of the shank of the bolt 2, a pair of oppositely disposed bolt operating cams 5 and 6 positioned to engage the normally outer side of the plate 4 at its opposite edges, a knob 7 turnably mounted in the 85 bolt casing 1 and secured at its inner end to one of the cams 5, a disc 8 turnably mounted in a plate 9 secured over the inner side of the casing 1, the disc 8 being secured to the other bolt operating cam 6, a cylinder or 90 tumbler casing 10 extending beyond the outer face of the door 1 and extending with its inner end into a transverse opening D¹ of the door, a plurality of pairs of cylinders or tumblers 11 and 12 mounted in the cylinder or tumbler casing 10, as shown best by dotted lines in Fig. 1, a plurality of compression springs mounted in the recesses of the cylinders or tumblers, as indicated by 105 13 in Fig. 1, a plug 14 adapted to receive 110

the key K and turnably mounted in the cylinder casing and retained in position relatively thereto by means of a retaining member 15, shown in Figs. 1, 2 and 3, a motion transmitting bar 16 secured at its one end in the member 15 and inserted with its other end in a slot 8^a in the disc 8, and a ring 17 for supporting and positioning the outer enlarged annular flange 10^a of the casing 10 at the normally outer side of the door.

In the locks now used the ring 17 is normally held in position by the flange 10^a of the cylinder or tumbler casing 10, the latter of which is held in position by a plate at the inner side of the door. However, in my construction the ring 17 is preferably fixedly secured at the outer side of the door by any suitable means, such as by a pair of bolts 19 extending through a plate 18 at the normally inner side of the door and positioned underneath the bolt casing 1. The bolts 19 are screwably secured at their normally outer threaded ends in threaded bosses 17^a, forming a part of the ring 17, as shown best in Figs. 1, 2 and 3. The ring 17 may be positioned relatively to the hole D¹ of the door D by means of an annular flange, as shown best in Figs. 1 and 2, and may be non-rotatably secured relatively to the door by means of pointed lugs 17^b, as shown in Fig. 1.

The inner end of the casing 10 is provided preferably with a laterally extended lug 10^b, to the extended end of which is secured, by means of a nut 21, the reduced threaded end of the cylinder casing positioning or securing member 20, which is in the form of a bar, as shown best in Figs. 3, 4 and 5. This bar may be offset, as shown in Fig. 2, if desired, to meet the interior construction of the bolt casing 1. The opposite end of the member 20 may be secured in a variety of ways to the casing 1 or the inner side of the door, so that the casing 1 need not be removed. In the structure as shown, the one side of the member 20, facing the free edge of the door, is provided with a plurality of close serrations or transverse grooves 20^a, as shown best in Fig. 2, into which is adapted to be extended a V-shaped or knife edge 9^a on the plate 9, as shown best in Fig. 2. The member 20 is preferably made sufficiently resilient so that the same will normally assume a position away from the V-shaped or knife edge 9^a, so that the member 20 may be readily inserted into and withdrawn from the opening 9^b without interfering with the V-shaped or knife edge, the latter edge forming one side of the opening 9^b of the member 9. At the inside of and near the rear end of the bolt casing 1 is provided a lug 1^b against which the normally free end of the member 20 is adapted to be forced. The normally free end of the

member 20 is secured against the edge 9^a of the plate 9 and against the lug 1^b of the casing 1 by means of a set screw 22 accessible and adjustable from the end and outside of the casing 1. When the set screw 22 is loosened, the member 20 will spring backwardly, as indicated by dotted lines in Fig. 2, thus permitting the casing 10 to be readily removed without removing the casing 1 or any other essential part of the lock assembly. The member 20 is also so constructed as to be readily fitted to various widths of doors, the serrations or transverse grooves permitting the end of the member 20 to be readily broken off with a pair of pliers to suit the width of the door.

Though I have shown and described a particular construction, combination and arrangement of parts and portions, I do not wish to be limited to this particular construction, combination and arrangement nor to the particular type of locks, but desire to include in the scope of my invention, the construction, combination and arrangement of parts and portions as applied to ordinary tumbler locks, locks combined with door knobs, as well as other locks now in use, substantially as set forth in the appended claims.

Having thus described my invention, what I claim as new and desire to secure by Letters Patent is:

1. In a lock structure, the combination with a door or the like, of a bolt casing mounted on the door, a bolt shiftably mounted in said casing, means for operating said bolt, a cylinder casing readily removably mounted on said door and provided with a key receiving plug adapted to be operatively connected with the means for operating the bolt, a cylinder casing positioning and securing bar secured at its normally outer end to the cylinder casing and extending into said bolt casing, and screw means for securing the opposite end of said bar relatively to said bolt casing, the one side of said bar being provided with transverse grooves providing retaining grooves for the cylinder casing for various widths of doors and providing means to facilitate the breaking of said bar into the desired lengths.

2. In a lock structure, the combination with a door or the like, of a key controlled cylinder portion registered on a ring on the outer side of said door, a bolt portion mounted on the inner side of said door in correct alignment with said ring and secured to said door, an independent plate mounted between said bolt portion and inner door surface, longitudinally adjustable means for securing said registering ring to said independent plate, further longitudinally adjustable means for locking said cylinder to said independent plate, and means on the

bolt portion for releasing said cylinder locking means.

3. In a lock structure, the combination with a door or the like, of a key controlled cylinder portion registered on a ring on the outer side of said door and provided with a laterally projecting lug, a bolt portion mounted on the inner side of said door in correct alinement with said ring and secured to said door, an independent plate mounted between said bolt portion and inner door surface, longitudinally adjustable means for securing said registering ring to said independent plate, and longitudinally adjustable means screwably secured to said laterally projecting lug on said cylinder for locking said cylinder to said independent plate.

4. In a lock structure, the combination with a door or the like, of a key controlled cylinder portion registered on a ring on the outer side of said door, a bolt portion mounted on the inner side of said door in correct alinement with said ring and secured to said door, an independent plate mounted between said bolt portion and inner door surface, longitudinally adjustable means for securing said registering ring to said independent plate, and locking means secured at its one end to said cylinder and removably securable at its other end to means on the inner side of the door.

5. In a lock structure, the combination with a door or the like, of a key controlled cylinder portion registered on a ring on the outer side of said door, a bolt portion mounted on the inner side of said door in correct alinement with said ring and secured to said door, an independent plate mounted between said bolt portion and inner door surface, longitudinally adjustable means for securing said registering ring to said independent plate, a locking means secured at its one end to said cylinder and at its other end to means on the inner side of the door, and further means for readily releasing said locking means from the inside of the door.

6. In a lock structure, the combination with a door or the like, of a key controlled cylinder portion registered on a ring on the outer side of said door, a bolt portion mounted on the inner side of said door in correct alinement with said ring and secured to said door, an independent plate mounted between said bolt portion and inner door surface, longitudinally adjustable means for securing said registering ring to said independent plate, and a resilient locking bar secured at its one end to said cylinder and

securable at a plurality of poistions over its other end portion to said independent plate. 60

7. In a lock structure, the combination with a door or the like, of a key controlled cylinder portion registered on a ring on the outer side of said door, a bolt portion mounted on the inner side of said door in correct alinement with said ring and secured to said door, and independent plate mounted between said bolt portion and inner door surface, longitudinally adjustable means for securing said registering ring to said independent plate, a resilient locking bar secured at its one end to said cylinder and securable at a plurality of positions over its other end portion to said independent plate, and means on the inner side of the door for disengaging said cylinder locking means. 70

8. In a lock structure, the combination with a door or the like, of a key controlled cylinder portion registered on a ring on the outer side of said door, a bolt portion mounted on the inner side of said door in correct alinement with said ring and secured to said door, an independent plate mounted between said bolt portion and inner door surface, longitudinally adjustable means for securing said registering ring to said independent plate, and a cylinder locking member secured at its one end to said cylinder, a portion of the other end projecting through an aperture in said independent plate and having a plurality of serrations capable of engaging said plate in locking position. 80

9. In a lock structure, the combination with a door or the like, of a key controlled cylinder portion registered on a ring on the outer side of said door, a bolt portion mounted on the inner side of said door in correct alinement with said ring and secured to said door, an independent plate mounted between said bolt portion and inner door surface, longitudinally adjustable means for securing said registering ring to said independent plate, a cylinder locking member secured at its one end to said cylinder, a portion of the other end projecting through an aperture 90 in said independent plate and having a plurality of serrations capable of engaging said plate in locking position, and a readily accessible means on the inner side of said door for releasing said cylinder locking member 95 from locked position. 100

In testimony whereof, I have hereunto set my hand at Carlsbad, California, this 11th day of January, 1926.

BENJAMIN H. PELTON.
